HORACE M. KAUFFMAN.
INVENTOR.

By George J. Oltach.
ATTORNEY.

UNITED STATES PATENT OFFICE.

HORACE M. KAUFFMAN, OF SOUTH BEND, INDIANA, ASSIGNOR TO THE SOUTH BEND MUSIC HOLDER MANUFACTURING COMPANY, A COPARTNERSHIP COMPOSED OF EARL K. PROCTOR, GEORGE M. STUDEBAKER, JR., AND HORACE M. KAUFFMAN, OF SOUTH BEND, INDIANA.

MUSIC-HOLDER FOR PIANOS.

1,082,639.

Specification of Letters Patent. Patented Dec. 30, 1913.

Application filed November 9, 1912. Serial No. 730,460.

To all whom it may concern:

Be it known that I, HORACE M. KAUFFMAN, a citizen of the United States, residing at South Bend, in the county of St. Joseph and State of Indiana, have invented certain new and useful Improvements in Music-Holders for Pianos, of which the following is a specification.

My invention relates to music holders for musical instruments, particularly pianos, organs, and the like.

In the common and well-known upright pianos now in use the music is supported on the upper pivoted panel, which is swung upwardly so that the music rests against the inclined panel, with its lower edge supported on a ledge or foot piece carried by the panel. But in this type of pianos it is impossible to adjust vertically the music so that children or persons of short stature can readily read the music without serious eye strain.

It is, therefore, one of the objects of my invention to provide a music holder adapted to be supported by the swinging panel of a piano or organ, or the like, that can be adjusted vertically.

It is a further object of my invention to provide a vertically adjustable music holder that can be disposed within a recess in the swinging panel, so as not to be in the way when the piano is closed or not in use.

A still further object of my invention is to provide a music holder that can be slid into a recess in the swinging panel of the piano and is of such size and thickness as to become flush with the surface of the swinging panel.

A still further object of my invention is to provide a music holder that is a complement to the swinging panel of the piano or other casing, the music holder being disposed in a recess in the panel.

With these and other objects in view, the present invention consists in the combination and arrangement of parts hereinafter more fully described, illustrated in the accompanying drawings, and particularly pointed out in the appended claims, it being understood that changes may be made in the form, proportions, size and minor details without departing from the scope or

sacrificing any of the objects of the invention.

Of the drawings, Figure 1 is a perspective view of a piano or piano casing with my improved holder applied thereto; Fig. 2 is an end view of my improved music holder with parts of the piano case shown in section; Fig. 3 is a horizontal section on the line 3—3 of Fig. 1, and Fig. 4 is a fragmentary rear view of the upper pivoted panel of the piano.

Upon referring to the drawings, A represents the upper pivoted panel of the piano case A'. This swinging or pivoted panel A is provided with a ledge or shelf A² along its lower end. Intermediate the ends of the panel A is a depression or recess A³, preferably rectangular in shape, in which recess or depression is normally disposed the music holder B. The vertical side ends of the depression A³ are under-cut, as at A⁴ (see Fig. 3) and the vertical side edges of the music holder B may be beveled so as to slide in these under-cut portions. The thickness of the music holder B is preferably equal to the depth of the recess or depression A³ whereby the outer surface of the music holder B is flush with the surface of the swinging panel A.

The ledge A² of the swinging panel A is cut away opposite the recess or depression A³ and the music holder B is provided at its lower end with a ledge or foot piece b preferably of the same size, thickness and contour as the ledge A², so that when the music holder B is slid into the depression or recess A³ so as to completely occupy the same, the ledge or foot-piece b will become flush with and aline with the ledge A² of the swinging panel A, thus forming a complement to the ledge A².

It will be noted that the area of the music holder B is substantially equal to the area of the depression A³ so that when the music holder B is disposed within the depression it completely occupies the same, and the upper end of the depression will serve as a stop to limit the upwardly sliding movement of the music holder B, thus obviating any danger of the ledge or foot piece b assuming a position out of alinement with the ledge A² when the music holder B is slid into

- the recess or depression A^3 , which non-alinement would tend to mar the beauty or ornamentation of the panel A or the piano case A'.
- 5 In the use of my invention, the panel A is swung outwardly and if it is desired to bring the music nearer the key-board, the music holder B is slid downwardly until the music holder assumes the desired position, whereupon the music is placed upon the music holder where it is supported by the ledge b and the back of the music holder. It will be seen that the music holder may be lowered to a position very close to the keys, so that children and people of short stature may readily read the music without serious eye strain, and can have ready access to the music so as to turn over the leaves. If it is not desired to lower the music holder 10 it will be unnecessary to slide the music holder B out of its recess or depression in the swinging panel, but the music may be supported upon the music holder B when in its normal position in the recess A^3 .
- 15 25 Ordinarily there is sufficient friction between the sliding music holder B and the panel A to support music of heavy weight, such as books, etc., thus overcoming any tendency of the weight of the music to cause the music holder B to drop downwardly with respect to the panel A. However, in order to limit the downward drop of the music holder, the same is provided with a pin b' , which projects through a slot A^5 in the panel A, which pin is adapted to contact with the front frame portion A^6 of the piano, and thus limit the downward movement of the holder, as plainly shown in Fig. 2.
- 30 35 40 Although the preferred form of my invention is to provide the panel A with a depression or recess A^3 , it is obvious that in lieu of a recess or depression the panel may be entirely cut out so as to accommodate the music holder B, suitable guide grooves being provided in the vertical side edges of the cut out portion to permit the music holder to be slid in or out of such cut out portion, the music holder B being preferably of the same thickness as the panel. It is obvious that I am not limited to the particular shape of the recess A^3 and music holder B, but recesses and music holders of different shapes may be used if desired.
- 45 50 55 55 What I claim is:
1. A piano having a pivotally mounted panel provided with a depression, the sides

of which are under-cut, and a music holder sliding in the depression with its surface flush with the outer surface of the panel. 60

2. A piano having a pivotally mounted panel provided with a depression, and a music holder comprising a plate sliding in the depression with its outer face flush with the surface of the panel. 65

3. In a piano, a pivotally mounted panel provided with a depression extending from near its center to the lower edge thereof, a ledge secured along the lower edge of the panel and provided with a cut-away portion 70 opposite the depression, a music holder comprising a slide provided with a ledge adapted to be slid into the depression with the ledge of the music holder in alinement with the ledge of the panel. 75

4. A piano having a swinging panel provided with a recess, a ledge along the lower edge of the panel, having a cut-out portion adjacent the recess in the panel, a music holder disposed in the recess in the panel, 80 and a ledge carried by the music holder and disposed within the cut-out portion of the ledge on the panel.

5. A piano having a swinging panel provided with a recess, grooved guides along 85 the opposing sides of the recess, a ledge carried by the panel and provided with a cut-out portion opposite the recess, a music holder slidably disposed in the recess in the panel and entering the grooved guides, and 90 a ledge carried by the music holder and complementary to the ledge on the panel.

6. A piano having a swinging panel provided with a recess, a ledge carried by the panel and having a cut-out portion opposite 95 the recess, a music holder disposed in the recess of the panel and complementary to the outer surface of the panel, and a ledge carried by the music holder and complementary to the ledge of the panel. 100

7. A piano having a swinging panel provided with a depression and a slot therein, and a music holder sliding in the depression and having a member extending through said slot adapted to rest upon the frame portion 105 of the piano to limit the downward movement of the holder.

In testimony whereof I affix my signature in presence of two witnesses.

HORACE M. KAUFFMAN.
